UNITED STATES PATENT OFFICE.

EMILE BERLINER, OF WASHINGTON, DISTRICT OF COLUMBIA.

TELEPHONE-TRANSMITTER.

SPECIFICATION forming part of Letters Patent No. 340,853, dated April 27, 1886.

Application filed August 17, 1885. Serial No. 174,610. (No model.)

To all whom it may concern:

Be it known that I, EMILE BERLINER, residing at Washington, in the District of Columbia, have invented certain Improvements 5 in Telephone-Transmitters, of which the following is a specification.

My invention relates to telephonic transmitters of that class in which a variation of contact produces a variation in the strength 10 of current. Transmitters of this general type have been devised heretofore which employ as the current-varying medium a number of balls or spheres of conducting material held between conducting-plates. These balls or 15 globules have sometimes been made of metal—such as lead shot—but balls of carbon have been found most suitable for this purpose. In practice, however, it has been found extremely difficult, in fact almost impossible, to produce 20 these small carbon spheres of exactly the same size, which is a necessary condition in instruments of this class, since otherwise the upper disk or plate does not rest evenly upon the balls, and in consequence more or less of 25 the latter are not included in circuit.

In addition to the initial difficulty of cutting or turning the carbon pieces into the form of perfect spheres of uniform size, there is still greater difficulty in preserving this uniformity during the process of smoothing and polishing the balls. As will be readily understood, a very slight variation in size will detract from the efficiency of the instrument.

The present invention is based upon the 35 discovery that the difficulties above stated may be obviated without sacrifice of the advantages attending this form of instrument by making the carbon pieces in the form of pencils or rods—*i. e.*, making their shape cylindrical instead of spherical, it being practically a simple matter to shape pieces of carbon into rods or cylinders of uniform diameter.

The construction of a transmitter in accordance with the invention is as follows: 45 One electrode is a conducting plate or diaphragm, preferably of carbon, which is rigidly fixed in position. Upon this plate rests a series of cylindrical carbon sticks varying 50 in length from the diameter of the plate or

diaphragm to the chord of a small arc thereof. Upon these carbon cylinders the second electrode rests by its own gravity, but otherwise free to vibrate. This second electrode should be of sufficient area or of such formation as 55 to make contact with all the carbon cylinders. I prefer a plate of carbon of substantially the same area as the diaphragm.

In the accompanying drawings, Figure 1 is a cross-section of the complete transmitter. 60 Fig. 2 is a detail view of part of the same.

A B is the case of insulating material, as wood or hard rubber, and is in two sections. Section A is recessed to receive the metal ring I, upon which rests the conducting plate or 65 diaphragm C, preferably of carbon. The case-section B is a ring having a flange to fit the recess in A. The two sections are held firmly together by screws a a, thus clamping ring I and diaphragm C firmly in position. Upon 70 diaphragm C there are a series of carbon cylinders, D, varying in length, as shown in Fig. 2, from about the diameter of the recess in case-section B to the chord of a small arc thereof. These cylinders are free to move, 75 and rest by gravity upon diaphragm C.

E is a plate of conducting material, as carbon, resting by its gravity upon the cylinders D. One circuit terminal, y, is connected to plate E. The second terminal, z, is connected 80 to diaphragm C through ring I.

The sounds for transmission are directed upon diaphragm C through mouth-piece G.

What I claim, and desire to secure by Letters Patent, is—

85

1. In a telephone-transmitter, the combination of a series of carbon rods resting loosely between a conducting diaphragm and a loose conducting-weight.

2. In a telephone-transmitter, the combination of two plates of conducting material forming the two electrodes of a circuit and a series of carbon cylinders located between them.

3. In a telephone-transmitter, the combination of two carbon plates forming the electrodes of a circuit and a series of carbon cylinders located between them.

4. In a battery-transmitter, the combination of a plate and diaphragm of conducting material forming one electrode of a circuit,

95

100

and two or more carbon cylinders forming the other electrode of said circuit.

5. In a battery-transmitter, the combination of a carbon plate or diaphragm rigidly fixed in position, a series of carbon cylinders resting upon said plate by their own gravity, and a plate of carbon resting upon the said cylinders.

6. In a telephone-transmitter, the combination of an inclosing-case in two sections, in one of which is located a metal ring, and a carbon diaphragm firmly held in position by the

second section, a series of carbon-cylinders resting upon the diaphragm and a carbon plate resting upon the cylinders.

In testimony whereof I have signed my name to this specification, in the presence of two subscribing witnesses, this 14th day of August, 1885.

EMILE BERLINER.

15

It is hereby certified that in Letters Patent No. 340,853, granted April 27, 1886, upon the application of Emile Berliner, of Washington, District of Columbia, for an improvement in "Telephone-Transmitters," an error appears in the printed specification requiring the following correction, viz: In line 99, page 1, the word "and" should read *or*; and that the Letters Patent should be read with this correction therein to make it conform to the record of the case in the Patent Office.

Signed, countersigned, and sealed this 11th day of May, A. D. 1886.

[SEAL.]

H. L. MULDROW,
Acting Secretary of the Interior.

Countersigned:

M. V. MONTGOMERY,
Commissioner of Patents.
